CLAIM

The ornamental design for a tire as shown and described.

DESCRIPTION

FIG. 1 is a side perspective view of a tire showing my new design;

FIG. 2 is a front elevational view thereof; it being understood that the pattern is repeated throughout the circumference of the tire;

FIG. 3 is a side elevational view of the left side thereof; FIG. 4 is a side elevational view of the right side thereof; and,

FIG. 5 is an enlarged fragmentary side elevational view taken from line 5-5 in FIG. 3 thereof.

In the drawings, the broken lines depict environmental subject matter only and form no part of the claimed design.
